CLAIM

The ornamental design for a light fixture, as shown and described.

DESCRIPTION

FIG. 1 is a bottom perspective view of a light fixture, showing my new design.

FIG. 2 is a front elevation view of the light fixture of FIG. 1, the rear elevation view being a mirror image of the front view.

FIG. 3 is a right side elevation view of the light fixture of FIG. 1, the left side elevation view being a mirror image of the right side view; and,

FIG. 4 is a bottom plan view of the light fixture of FIG. 1.

Portions or features of the light fixture not shown in the drawings form no part of the claimed design. The broken lines in the drawings form no part of the claimed design.

The broken lines illustrate portions of the light fixture which form no part of the claimed design.

1 Claim, 2 Drawing Sheets
